UNITED STATES PATENT OFFICE.

HENRY A. WHEELER, OF JACKSONVILLE, FLORIDA.

SHINGLE.

Application filed September 27, 1923. Serial No. 665,197.

To all whom it may concern:

Be it known that I, HENRY A. WHEELER, a citizen of the United States, residing at Jacksonville, in the county of Duval and State of Florida, have invented certain new and useful Improvements in Shingles; and I do declare the following to be a full, clear, and exact description of the invention, such as will enable others skilled in the art to which it appertains to make and use the same.

In roofing tobacco barns, it is essential that ventilating passages be provided from interior to exterior and while numerous attempts have been made to produce a more lasting roof and one having greater fire resistance, the only roofs in use today, consist of spaced roofing lath and ordinary wooden shingles laid thereon with their edges in spaced relation to provide for ventilation. Hence, it is an accepted fact in the tobacco industry that if a more permanent roof is to be produced, one which is fire resisting, and one which may be sold at a price which is not prohibitive, such roof must be obtained by the use of wooden shingles treated to increase their life and to resist fire to the maximum. This end I seek to obtain by my invention.

With the foregoing in view, the invention resides in the novel subject matter hereinafter described and claimed, the description being supplemented by the accompanying drawing.

Figure 1 is a perspective view of a portion of the improved roof.

Figures 2 and 3 are respectively, longitudinal and transverse sectional views of one of the shingles.

I make use of an ordinary wooden shingle designated in the drawing by the numeral 1 and this shingle need not be of first grade quality. The upper side of the shingle is thickly coated with high flash point asphalt 2, and the coating 2 is in turn coated with crushed slate 3, or other weather and fire resisting substance. The coating 2-3 extends from the lower end of the shingle to its upper end for an important purpose set forth below, and constitutes a marked differentiation between this invention and certain prior shingles. As indicated at 4, the thick coating of asphalt and slate or the like, extends around the edges of the shingle, and to prevent dry rotting, the lower side of the latter is preferably pro-

vided with a relatively thin asphalt coating 5.

The coating 2-3 is not of a brittle nature, and under fire heat is convertible into a thick viscous fluid which is adapted to slowly run, for a purpose to be set forth below. This further distinguishes my invention in an important manner from coated shingles heretofore devised.

The shingles are laid in the usual way upon spaced roofing lath 6, being sufficiently stiff to permit this, which is not true of a number of coated, composition shingles on the market. Spaces are left between the shingle edges to provide ventilating passages 7. A roof formed in this manner, provides for the necessary ventilation and weather protection and is fire resistant to a high degree. If one of the shingles should catch fire, the coating 2-3 will not blaze violently but will slowly smolder unless forcibly fanned. If the fire should burn through this shingle, it encounters the coating 2-3 of the underlying shingles and is thus further resisted against burning through the roof, and the heat from the fire converts the coating 2-3 into a thick, viscous fluid which runs into the ventilating passages 8 and seals them, so that the fire cannot creep through said passages to the interior of the roof. It will thus be seen that burning of the fire through the roof and spreading over the surface thereof is resisted to a high degree.

The improved roof may be constructed more cheaply than a roof formed of good grade wooden shingles of the type now used, and a wooden shingle of poor grade treated in accordance with my invention, produces a better and more serviceable article than the best grade wooden shingle now sold. Thus, inexpensive manufacture does not produce an inferior product, but an improved one, which has the additional advantages of reducing fire hazard to a great extent and consequently greatly lowering insurance rates.

The construction disclosed is preferable, but within the scope of the invention as claimed, minor changes may be made.

I claim:

A wooden shingle adapted to be laid in overlapping relation with other shingles upon spaced roofing lath and adapted to have its edges spaced from adjacent shingle edges to form ventilating passages, a

thick fire-resisting plastic coating of uniform thickness over the entire upper side and extending around the edges of said shingle to resist fire on the portion of the shingle exposed to the weather and to also resist fire burning through an overlapping shingle, said coating being convertible by

fire heat into a thick viscous fluid adapted to run into and seal the above-mentioned ventilating passages to resist passage of fire therethrough to the interior of the roof.

In testimony whereof I have hereunto affixed my signature.

HENRY A. WHEELER.
